CONTAINER

Harry W. Jones, Knoxville, Tenn., assignor to Dempster Brothers, Incorporated, Knoxville, Tenn., a corporation of Tennessee

Application August 29, 1955, Serial No. 531,137

6 Claims. (Cl. 294—73)

This invention relates to an improved container of the type adapted to be elevated along an upright skid frame or the like to a transporting and/or dumping position and more particularly to such a container, adapted for use with equipment other than transporting and dumping devices, and provided with disappearing-type lifting pins to reduce the lateral dimensions of the container.

By way of example, containers of the type to which the invention relates may be used in conjunction with transporting and dumping equipment such as illustrated in U. S. Patent No. 2,179,779 for transporting and dumping the containers and may be used with equipment such as that illustrated in U. S. Patent No. 2,725,584 for purposes of loading the container. The invention is not restricted to containers so used but this patent and application will be referred to hereinafter for purposes of illustration.

Such containers are elevated by lifting links or hooks or the like which are attachable to and detachable from suitable means such as projecting pins located on each end wall of the container approximately in the vertical center plane thereof. During its elevation, movement of the container is guided and tilting and/or overturning thereof are prevented by skidding engagement of one of the container side walls with the skid frame. For transporting or storage purposes, the skid frame is then moved forwardly on its support and the elevated container lowered to rest on the support, e. g., a vehicle chassis in the example under consideration. For dumping purposes, a bail located at or near the top of one side wall eventually reaches and engages an elevated suspension hook or its equivalent. Then the container can be dumped by tilting it about the point of attachment of the bail thereto, or by allowing a drop-bottom to open.

Under normal conditions such containers can be handled as described above without any difficulty whatsoever, as attested by the widespread use of this type of equipment. In some cases, however, as in the use of the container with apparatus as disclosed in Patent No. 2,725,584, referred to above, it is desirable and necessary for the lateral dimensions of the container to be held to close tolerances so that the container may be used with equipment requiring a close or secure fit therewith. Under these circumstances permanent extension of the lifting pins from the side walls of the container is undesirable since the lifting pins will engage with other parts of the apparatus and interfere with the proper use of the container while at the same time requiring an excessively large aperture in the apparatus to receive the container. Reduction of the over-all width of the container by providing lifting pins which will disappear into the side walls of the container is therefore necessary for a proper handling of the container in the using apparatus, as will be explained in greater detail hereinafter, and an object of the present invention is to provide an improved container of reduced over-all width for use under such special conditions which can also be handled by transporting and

2

elevating equipment or like elevating apparatus in the normal manner and without difficulty.

Another object is to provide such a container having lifting pins which can disappear within the side walls of the container to reduce the lateral dimensions of the container or which can be raised for cooperation with the transporting and dumping equipment or other apparatus of the type in question.

One embodiment of the invention has been illustrated 10 in the accompanying drawings, but it is to be expressly understood that said drawings are for purposes of illustration only and are not to be construed as a definition of the limits of the invention, reference being had to the appended claims for this purpose.

Fig. 1 is a front elevation (i. e., from the bail wall side) of an embodiment of the container of the present invention showing the lifting pin pivoted within the side walls of the container and rotated into position for engagement by the lifting links or the like;

Fig. 2 is a side view of the embodiment of Fig. 1 as seen from the right therein showing a lifting pin in raised position for engagement by the lifting links or the like and further showing a construction for the aperture in the side wall of the container into which the lifting pin rotates when not in use;

Fig. 3 is a view partly in section on the line 3—3 of Fig. 4 and showing a construction for the aperture in the side wall of the container for receiving the lifting pin when not in use and the construction of the pivot of the lifting pin;

Fig. 4 is a view from the right of the detail of Fig. 3; and

Fig. 5 is a partial interior view of a side wall of the container of Fig. 1 showing a construction for the aperture receiving the lifting pin, the arrangement of baffle plates to prevent lodging of material behind the walls of the aperture and the arrangement of the guide strip with respect thereto.

Referring now more particularly to Figs. 1 and 2, the 40 container there shown is of the well known drop-bottom type. The container is elevated on the transporting and dumping equipment by means of lifting pins 10 and 11, each such pin being located approximately centrally in its respective end wall of the closed container. As will be 45 understood by those familiar with this art, drop-bottom 12 is provided with triangular wings 13 and 14 at each end thereof and the lifting pins 10 and 11 are located near the apices of these wings so that as the lifting links or the like elevate the container, they also hold the drop-bottom 12 in closed position.

In the form of container chosen for illustration of the invention, a special shape is employed in which the right-hand upper corner of the container (as seen in Fig. 2) is removed, leaving a beveled or inclined wall 15 and the left-hand upper corner of the container is also removed, leaving a similar beveled or inclined wall 16, this shape being of advantage when such containers are employed with apparatus, such as street sweepers, as disclosed in Patent No. 2,725,584. A bail 17 is located 55 at the top of the bail wall 18, projecting upwardly therefrom to substantially the same level as the top edge 19 of the container. Bail 17 is pivoted at 20 and is received in a suitable recess 21 formed in inclined wall 16 so that bail 17 may be moved to a position in the recess where 60 it will not interfere with use of the container in apparatus such as the street sweeper referred to above. This arrangement, for rotating and telescoping the bail is disclosed and claimed in U. S. Patent No. 2,758,733.

When the container of the present invention is to be 65 used with sweeping apparatus, such as identified above, the triangular wings 13 and 14 are provided at their apices with fixed projecting pins 22 and 23 which are engaged

by the lifting devices of the sweeper apparatus to elevate the container into its position in the apparatus and to hold bottom 12 of the container in closed position while the container is in the sweeping apparatus.

Guide strips are preferably provided for the edges of triangular wings 13 and 14 and, as shown in Fig. 2, one such guide strip 24 is mounted externally to overlap the right-hand edge of wing 13 and the adjacent edge of the side wall 25 of the container, being suitably secured as by welding to one of these parts, for example, the side wall 25. A similar guide strip 26 is mounted to overlap the inside of the left edge of wing 13 and the adjacent edge of said wall 25 and is suitably secured as by welding to one of these parts, for example, the side wall 25.

The construction of lifting pins 10 and 11 and of the apertures for receiving these lifting pins in lowered position are identical and it will therefore be necessary to describe this structure only with respect to one such lifting pin and, for purposes of illustration, this structure will be described with respect to lifting pin 10. As best seen in Figs. 2-5, wing 13 is rectangularly cut away at 27 to form a rectangularly shaped aperture therein. Aperture 27 is boxed in interiorly of the container by a side wall 28, a rear wall 29, a second side wall 30 and a top 31, these several elements being suitably joined, as by welding, to each other, to the bottom 12 of the container and to the edges of aperture 27. The upper edge 32 of aperture 27 may be suitably reinforced interiorly by a reinforcing strip 33 which is suitably secured thereto as by welding and is also secured to the adjacent portions of side walls 28 and 30 and top 31. A baffle plate 34 extends from the joining edges of back 29 and side wall 30 extends angularly and rearwardly therefrom to engage wing 13 at 35, baffle 34 being suitably secured to adjacent elements as by welding. A top 36 extends from baffle 34 to wing 13 and to the adjacent edge of top 31 and is suitably secured to these elements as by welding. Baffle 34 and top 36 are provided so that material to be dumped will not lodge between side wall 30 and wing 13.

A horizontal cylindrical pin 37 extends between side walls 28 and 30 and is spaced from rear wall 29. Reinforcement around pin 37 at side walls 28 and 30 may be provided by bearing blocks 38 and 39 suitably secured to their respective side walls.

Lifting pin 10 is mounted for rotation on pin 37 and extends downwardly within the box-type enclosure surrounding aperture 27 when not in use. Pin 10 extends laterally outward from wing 13 in raised position and in engagement with edge 32 of aperture 27 and reinforcing block 33 for engagement by the lifting links or the like. Lifting pin 10 is seen to comprise side pieces which are mounted on the ends of a sleeve 40 as by means of welded connections 41, the sleeve being rotatable on the pin 37. The side pieces are provided with inturned portions 42 and 43 and with outer parallel portions 44 and 45. A cylindrical pin 46 is suitably secured between parallel portions 44 and 45, as by welding, and terminates in a cap 47. A reinforcing plate 48 is secured to the inner end 49 of pin 46 and is mounted on sleeve 40 in a manner similar to the side pieces. The side pieces and the plate 48 are tied together by a top plate 50 and if desired by one or more bottom tie plates 51. The side pieces are provided with suitable shoulders 52 to engage rear wall 29 when pin 10 is in lowered position to hold the end of pin 10 and the cap 47 away from rear wall 29 for easy manual engagement.

With this construction of the lifting pins 10 and 11 it is now readily apparent that when the lifting pins are not in use they will rotate under the action of gravity into position within the container adjacent the apertures in wings 13 and 14, respectively. When in this lowered position the lifting pins do not extend beyond wings 13 and 14 so that the container can be handled by the sweeping apparatus without danger of engagement of the

lifting pins with elements of such sweeper apparatus. On the other hand, the lowered pins 10, 11 can easily be swung by hand into their outwardly extending positions for engagement by the lifting links or the like of the transporting and dumping equipment. To insure that the pins remain in this position and are not accidentally dislodged therefrom during handling of the container, it may be desired to provide suitable retaining means. As shown, an eyelet 53 is suitably secured as by welding to the top plate 50 of each lifting pin, and a short length of chain 54 is attached to each eye and provided at its end with a ring-like member 55 adapted to fit over the pin 22 or 23 and hold the pin 10 or 11 in position. When the pins 10 and 11 are lowered, the members 55 can conveniently be secured by hooking them over fingers 56 welded to the eyelets 53.

It should now be apparent that this invention satisfies the several objects detailed above.

It will be understood, of course, that the invention is not restricted to the details of construction set forth in the illustrative example described above, and that various details can be made in the form and arrangement of the parts without departing from the spirit of the invention. Accordingly reference should be had to the appended claims for a definition of the limits of the invention.

What is claimed is:

1. A container of the type adapted to be elevated and supported during dumping and having a bottom rotatable to open dumping position with upstanding wings on opposite edges of the bottom forming portions of the side walls of the container when in closed position, a lifting pin mounted for rotation on a horizontal axis adjacent the upper middle portion of each of the upstanding wings, means on said wings engageable with said lifting pins to maintain the same in raised outwardly projecting positions, and a recess in each of the upstanding wings receiving said lifting pins when rotated into lowered position.
2. A container as defined in claim 1 in which a horizontal member is provided interiorly with respect to the side walls of the container and adjacent the top of each recess with each lifting pin rotatably mounted on the adjacent horizontal member for rotation into lowered position within the container.
3. A container as defined in claim 1 including box-type housings mounted within the container opening outwardly through apertures in said wings, a horizontal member in each housing mounted in opposite walls thereof and extending parallel to the adjacent wing, with one of said lifting pins mounted for rotation on each of said members, each lifting pin rotating into the adjacent housing when in lowered position.
4. A container as defined in claim 3 having baffles mounted adjacent each of said housings and extending to the adjacent wing preventing contents of the container from lodging between each of said housings and the adjacent wing.
5. A container of the type adapted to be elevated and supported during dumping and having a bottom rotatable to open dumping position with upstanding wings on opposite edges of the bottom forming portions of the side walls of the container when in closed position, a housing within the container having side walls, a rear wall and a top opening through each of said wings adjacent the middle thereof and secured thereto and to the bottom of the container, a horizontal member extending between said side walls of each of said housings and adjacent the top thereof and adjacent the top of the adjacent wing, a lifting pin rotatably mounted on each of said horizontal members for rotation into its respective housing when in lowered position and extending outwardly of its respective wing when in raised position and means on said wings engageable with said lifting pins to maintain the same in raised outwardly projecting positions.

6. A container as defined in claim 5 having baffles extending from an interior edge of each of said housings angularly toward the adjacent wing preventing the contents of the container from lodging between each of said housings and the adjacent wing.
